UNITED STATES PATENT OFFICE.

JAMES B. RICKETTS, OF NEW YORK, N. Y., ASSIGNOR TO THE NIGHTINGALE COMPANY, A CORPORATION OF NEW YORK.

INCINERATOR.

1,106,317.

Specification of Letters Patent.

Patented Aug. 4, 1914.

Application filed June 3, 1912. Serial No. 701,176.

To all whom it may concern.

Be it known that I, JAMES B. RICKETTS, a citizen of the United States, residing at New York, borough of Manhattan, State of New York, have invented a certain new and useful Improvement in Incinerators, of which the following is a specification, reference being had therein to the accompanying drawings.

10 This invention relates to incinerators to be used for the storage and destruction of any matter that it is desired to destroy by fire, but it is especially intended for application to the construction of incinerators 15 used for the destruction of garbage and other combustible refuse matter.

The present invention contains improvements upon the device shown in my prior application filed Dec. 14, 1911, Serial No. 665,611. In one form of construction shown 20 in said prior application the burner illustrated was a gas burner and in the form of grate construction shown in connection with the burner, in said application the gas must 25 pass through grate bars before impinging upon the matter to be destroyed in the combustion chamber, and in so doing much of its power is wasted before coming in contact with the matter to be consumed. On account 30 of the excessive heat on the grate bars the life of the same is greatly curtailed.

One object of the present invention is to construct the grate with openings so located 35 with relation to the openings in the gas burner that the gas flame will pass through without coming in contact with the grate itself and impinge itself immediately upon the matter to be consumed.

Another object of the invention is to provide 40 a means whereby the gas burner may be lighted from the outside of the machine without resorting to the usual method of a pilot light.

The invention will be fully understood 45 from the following description taken in connection with the accompanying drawings and the novel features will be pointed out and clearly defined in the claims at the close of the specification.

50 In the drawings: Figure 1 is a vertical section of a device embodying the invention. Fig. 2 is a cross section on line 2—2 of Fig. 1. Fig. 3 is a perspective view enlarged of one of the grates removed.

55 The device comprises a primary combustion

60 chamber for the reception of the garbage or other refuse, a fire chamber beneath the primary combustion chamber, a secondary combustion chamber located above the primary combustion chamber within which 65 the gases arising from the matter in the primary combustion chamber are destroyed, fire ducts leading from the fire chamber around outside of the primary combustion chamber into the secondary combustion 70 chamber and preferably also comprises a deflector and auxiliary burner.

Referring now to the drawings, the primary combustion chamber has side walls 1, and a dumping grate forming the bottom 70 of the combustion chamber. This dumping grate is preferably formed in two companion sections, each section being of angular shape and formed with a shaft 3 at the junction of the two wing portions 4, 5 by which 75 it is mounted in its bearings. Each grate section has a wing portion 4 which extends from the shaft 3 preferably at an upward inclination toward the wall and on which the matter to be consumed mainly rests. It 80 is also formed with a wing portion 5 which extends at an upward inclination toward the middle of the combustion chamber. The two wing portions 4, 5 of the two grate sections in the operative position thereof approach to a meeting line above at their upper edges, and form a hood outside of the burner itself.

It is to be observed that each grate member or section is of such form in cross section as to produce a pocket or recess in the upper side thereof, and when the structure is in use the pocket is filled constantly with a limited amount of the refuse to be consumed. It will be noted, furthermore, that 90 in the operative position of the grate members, as shown in Fig. 1, the wings 5 thereof extend upwardly and inwardly toward each other, the general direction of such wings being on converging lines. This construction and arrangement of the grate members 95 performs several important functions; first, the wings in the operative position of the grate members produce a hood which encases the upper side of the burner, as heretofore mentioned; second, the mass of solid material at the lower part of the primary combustion chamber is divided by the converging wings, and, third, the oppositely inclined wings direct the solid material in 100 105 110 115

two directions away from the central vertical part of the primary combustion chamber and into the pockets of the respective grate members. As a result, the pockets of said 5 grate members are charged or filled with relatively small quantity of the refuse, and the flames from the burner are brought into contact with such small quantities of refuse, thus facilitating the incineration thereof.

10 The burner 6 extends through the machine and is formed with a series of openings 7 on each side of the burner, these openings being so located that the gas flame will be sent out in a lateral direction, substantially 15 horizontal. The wing portion 5 of each grate section is formed with a lower or base portion 8, which extends upward in a more nearly vertical direction than the upper portion of the wing. This base portion 8 is 20 formed with large openings 2 so located that the gas flame will pass from the burner directly through said openings and impinge upon the matter to be burned which rests upon the wing portion 4, and within the 25 pocket of the grate member. The upper part of the wing portions 5 are formed as a series of bars with spaces between them through which the ashes may drop, and through which the deflected heat will pass 30 up into the garbage immediately above the burner. The wing portion 4 is also formed with a series of openings 9 through which the ashes may drop. A hood 10 is provided above the top of the burner 6 to protect the 35 same from ashes falling from the grate. The side walls 1 of the combustion chamber are formed at the lower ends with inwardly sloping flange portions 11 which project slightly over the wing portions 4 of the 40 grate so that any drippings in the combustion chamber will be carried down and fall onto the grate wing 4 and follow the slope of the grate, and then drop to the trough 12 so located as to receive the drippings. These 45 drippings will then be evaporated by the deflected heat.

A casing 13 surrounds the combustion chamber and extends to some distance above and below this chamber. In the lower part 50 of the casing 13 is the fire chamber 14, within which is located the burner 6 previously described.

The primary combustion chamber is formed with a top 15 having an opening 16 55 and the casing 13 which extends above the primary combustion chamber is formed with a top 17 having an opening 18 leading to the smoke flue. Between the top of the primary combustion chamber and the top 60 of the casing is the open space 19 which I term the secondary combustion chamber and in this secondary combustion chamber there is preferably located a chambered deflector 20 which contains an auxiliary burner 21.

65 Flanges 22 project from the side walls 1

of the primary combustion chamber into the fire ducts 23 between the primary combustion chamber and the casing, and deflectors 27 also project from the casing 13 into the fire ducts. The wings 4 of the grate are 70 also preferably formed with flanges 28 at their outer ends which extend at a downward inclination for the purpose of retarding the free passage of the burning gases from the fire chamber through the fire ducts. 75

In order to light the burner without the aid of a pilot light or gaining access to the interior of the machine the burner 6 is extended through the front of the casing to the outside thereof and is formed with perforations 29 in that portion which is between the combustion chamber and the front casing. A sleeve 30 surrounds that portion of the burner between the front casing and the wall of the fire chamber, being of larger 80 diameter than the burner, so that there is a space between the burner and the said sleeve, and there is also an opening 31 through the front casing into the end of said sleeve. When it is desired to light the burner if the cock is turned to turn on the gas a lighted match may be applied to the opening 31 at the outside, and sufficient gas will escape through the openings 29 so that it will be immediately ignited by the match, and the gas being thus ignited will follow through and ignite the gas in the burner within the fire chamber.

From the foregoing description taken in conjunction with the drawings, it will be noted that my invention embodied a dumping grate adapted to substantially incase the burner, for the purpose of supporting the material to be consumed in such relation to the burner that the flame emanating from said burner will come into direct contact with the material to be consumed. As shown, said grate is composed of two sections, said sections having upwardly converging members adapted to extend over the burner for supporting the material. The grate sections are movable for the purpose of dumping the unconsumed material, said grate operating to dump the material away from the burner, whereby lodgment of the unconsumed material upon the burner is precluded, so that the flame openings of the burner will not be obstructed by the material. Furthermore, the evaporating tray 12 is in such relation to the grate that liquid from the material resting upon the grate will be drained or flow by gravity into said tray. The tray is positioned below, and in close relation to, the burner so that the heat from the burner will evaporate the liquid contents of the tray. Said evaporating tray is mounted to dump in unison with the grate for the purpose of discharging any solid material which may fall by gravity into the tray. The tray is dumped simulta-

neously with the dumping movement of the grate, and the unconsumed material from both the tray and the grate may be discharged into a receptacle positioned in the lower part of the incinerator.

What I claim is:

1. In an incinerator, the combination with a combustion chamber, of a grate element embodying two wings positioned substantially at an angle to each other, one of said wings being provided with a flame opening separate from the openings produced in the grate bars, and a burner positioned in such relation to the grate element that the flame emanating therefrom will pass through the separate flame opening and into direct contact with the material imposed upon said grate element.

2. In an incinerator, the combination with a combustion chamber, of a grate element embodying a material-supporting wing and a second wing extending upwardly from said first named wing, said second wing being provided with a flame opening separate from the openings produced by the bars of said grate element, and a fuel burner separate from the grate, said fuel burner being positioned in such relation to the grate element that the flame from said burner is free to flow through the separate opening in the grate element and into direct contact with the material supported thereon.

3. In an incinerator, the combination with a combustion chamber, and a fuel burner, of a two-part grate the members of which are pivoted for movement independent of and relatively to said burner, said grate members embodying material supporting wings and other wings extending upwardly from the first named wings, said second named wings being arranged, in the operative position of the grate, to substantially incase the burner and preclude the lodgment of material thereon.

4. An incinerator having a combustion chamber to receive the matter to be incinerated, a grate forming the bottom of the combustion chamber, said grate having a wing portion which extends at an upward inclination within the combustion chamber, and a gas burner separate from the grate and located beneath said wing, said wing being formed with a substantially perpendicular part upon which no material can rest and in which part are provided openings through which passes the gas flame emanating from the burner, whereby the gas flame impinges directly upon the matter in the combustion chamber.

5. An incinerator having a combustion chamber for the material to be incinerated, a grate forming the bottom of the combustion chamber, said grate being formed in a plurality of disconnected sections, two adjacent sections of which each have wing portions

extending at an upward inclination toward each other so that their upper sides diverge from each other downwardly and form an outwardly sloping support for the matter in the combustion chamber, and a gas burner located beneath the grate in the space between the said diverging wing portions of the grate, said grate sections being operable to individually dump the material resting thereon.

6. An incinerator having a combustion chamber for the material to be incinerated, a grate forming the bottom of the combustion chamber, said grate being formed in a plurality of sections, two adjacent sections of which each have wing portions extending at an upward inclination toward each other so that their upper sides diverge from each other downwardly and form an outwardly sloping support for the matter in the combustion chamber, and a gas burner located beneath the grate in the space between the said diverging wing portions of the grate, said grate being formed with openings through which the gas flame from the burner will pass and impinge directly on the matter to be incinerated within the combustion chamber, said grate sections being operable to individually dump the material resting thereon.

7. An incinerator having a combustion chamber, a grate forming the bottom of the combustion chamber, a fire chamber beneath the grate, a casing surrounding the fire chamber, a burner within said fire chamber extending out through the wall of the fire chamber and through the wall of the casing, a sleeve surrounding that portion of the burner between the wall of the fire chamber and the casing, the said burner having a series of apertures both within the fire chamber and within the space between the fire chamber and the casing, said sleeve having an opening through the casing to the outside whereby the gas escaping from the burner into said sleeve may be directly ignited from the outside.

8. An incinerator having a combustion chamber, a grate forming the bottom of the combustion chamber, a fire chamber beneath the grate, a casing surrounding the fire chamber, a burner within said fire chamber extending out through the wall of the fire chamber and through the wall of the casing, a sleeve surrounding that portion of the burner between the wall of the fire chamber and the casing, the said burner having a series of apertures both within the fire chamber and within the space between the fire chamber and the casing, said sleeve having an opening through the casing to the outside whereby the gas escaping from the burner into said sleeve may be directly ignited from the outside, said grate being formed with openings through which the gas flame passes

from the burner and impinges directly on the material within the combustion chamber.

9. In an incinerator, the combination with a combustion chamber, and a fuel burner, of a two-part dumping grate the members of which are separate from the burner and are pivotally supported for movement relatively thereto, said grate members being positioned to substantially incase the burner in the operative position of said grate, said grate members being provided with flame apertures in substantial register with the flame apertures of the burner so that the flames emanating from said burner will pass through said apertures within the grate members and into direct contact with the material.

10. In an incinerator, the combination with a combustion chamber, and a fuel burner, of a two-part grate the members of which are separate from the burner and are pivoted at the respective sides thereof, said grate members being provided with wings which converge upwardly and substantially incase the burner against the lodgment of refuse material thereon, and said grate members being provided below the wings with flame slots so related to the burner that the flames therefrom will pass into direct contact with the refuse material adapted to be supported on said grate.

11. In an incinerator, the combination of a chamber adapted to contain the material to be consumed, a gas burner positioned in a plane intermediate the walls of said chamber, said burner having flame apertures positioned to direct the flame horizontally, and a two-part dumping grate operable to discharge the material in a direction away from said burner, said grate having openings in substantial register with the flame apertures of the burner, and said two parts of the grate being provided with upwardly converging members arranged to substantially incase the burner.

12. In an incinerator, a grate member embodying wings inclined relative to each other and affording surfaces for supporting the material, said grate member having a portion positioned substantially perpendicular, said perpendicular portion having openings, combined with a burner positioned in cooperative relation to the grate for the flame emanating therefrom to pass through said openings.

13. In an incinerator, the combination with a combustion chamber, of a dumping grate for supporting material within, and discharging burned refuse from, said chamber, said grate embodying material supporting members and other members extending upwardly from said material supporting members, said upwardly extending members being positioned intermediate the walls of the combustion chamber for dividing the

material therein and for directing said material toward the walls of the combustion chamber, whereby relatively small quantities of the material are adapted to be carried by the grate, a burner separate from said grate and positioned to burn the relatively small quantities of material upon said material supporting members of the grate.

14. In an incinerator, the combination with a combustion chamber, of a grate embodying a plurality of grate members pivoted for dumping movement, said grate comprising material supporting wings and other wings extending upwardly from the plane of said material supporting wings, said upwardly extending wings being positioned adjacent to each other and intermediate the walls of the combustion chamber for dividing the material present within said chamber and for directing the same toward the material supporting wings, a burner separate from said grate members and occupying normally a fixed position and in cooperative relation to said grate for burning the material carried upon the material supporting wings, and means for supplying fuel to said burner independently of the dumping movement of said grate members.

15. In an incinerator, a grate comprising separate members pivoted for dumping movement on horizontal axes, each member being substantially angular in vertical cross section and forming a pocket in the upper surface of the grate for containing a relatively small quantity of the material to be consumed, in combination with a burner separate from the grate and occupying normally a fixed relation to the dumping grate members, said burner being positioned to direct the flame into the pockets of the grate members for burning the small quantities of material therein.

16. In an incinerator, a grate comprising a plurality of separate members pivoted for dumping movement on horizontal axes, each grate member embodying a material supporting wing and another wing extending upwardly from said material supporting wing, said wings being relatively positioned for forming pockets in the upper surface of the grate wherein relatively small quantities of material are adapted to be contained, in combination with a burner separate from the grate, said burner being positioned for burning the small quantities of material present in said pockets.

17. In an incinerator, a plurality of grate members each embodying a material-supporting wing and an upwardly extending wing, the two wings being relatively positioned at an angle to produce a pocket in the upper side of the grate member, and each grate member being pivotally supported for movement substantially at the point of jun-

- ture of said wings, in combination with fuel burning means separate from the grate members and occupying a stationary relation to said grate members during the dumping movement thereof, said fuel burning means being in co-operative relation to the grate members for burning the material present within the pockets of said grate members.
18. In an incinerator, a plurality of grate members each comprising two wings which are relatively positioned to produce a pocket in the upper side of the grate member, one wing of each grate member extending upwardly toward a similar wing of the other grate member and the said upwardly extending wings operating to divide the material to be consumed, said grate members being separately pivoted for dumping movement relative to each other in combination with fuel burning means separate from the independently pivoted grate members and positioned in such relation thereto as to burn the material adapted to be contained in the pockets of said grate members.
19. In an incinerator, the combination with a combustion chamber, and a burner provided with flame apertures, of a grate the members of which are separately pivoted for dumping movement with respect to said burner, said grate embodying upwardly extending wings which converge so as to substantially incase the burner, said grate members being provided with flame apertures positioned in substantial register with the flame apertures of the burner so that the flame therefrom is free to pass into direct contact with the material adapted to be supported upon the grate.
20. In an incinerator, the combination with a combustion chamber, and a burner positioned in a space below said chamber, of a grate embodying a plurality of members pivoted for dumping movement relatively to the burner, said pivoted members having wings extending upwardly and over the burner, and a hood positioned intermediate the burner and the upwardly extending wings of said grate.
21. In an incinerator, the combination with a combustion chamber, of a non-rotative burner positioned in a space below said chamber, a hood partially incasing the burner and occupying a normally fixed relation thereto, and a dumping grate independent of the burner and the hood and mounted for movement relatively thereto, said grate embodying members extending upwardly toward each other and over said burner and hood.

In testimony whereof I affix my signature, in presence of two witnesses.
